Limburg, Heerlen, Netherlands

Application August 14, 1946, Serial No. 690,565
In Great Britain July 23, 1945

2 Claims. (Cl. 183—83)

1

This invention relates to cyclones used in concentrating or separating operations. Such a cyclone ordinarily comprises a cylindrical portion and a conical portion and means for delivering the material to be treated tangentially through an opening in the cylindrical portion. In the cyclone, rotating material in the vortex chamber spirals in an outer stratum toward the apex opening and discharges therethrough, and a hollow rotating inner stratum moves toward and through an opening in the opposite end of the cyclone.

Among the objects of the present invention are to increase the efficiency of such apparatus by an improved proportioning and relationship of parts, and to provide for the ready replacement of certain parts which are especially subject to wear.

The invention is shown in illustrative embodiment in the accompanying drawing in which

Figure 1 is an axial section of a cyclone.

Figure 2 is an axial section on a smaller scale of the apex end of a cyclone, showing a modification,

Figure 3 is a transverse section of an overflow hood, showing a modification, and

Figure 4 is an axial section of a cyclone chamber of modified form.

Referring to Figure 1, reference numeral 10 designates a short cylinder provided at its ends with outwardly extending flanges 11 and 12, the cylinder being here shown as disposed on a vertical axis. Reference numeral 13 designates a tapered inlet pipe which debouches into the cylinder 10 through an opening 14, the pipe, as here shown, being inclined downwardly to the cylinder at an angle of about 5° to the horizontal.

Below the cylinder 10 is a cone generally designated at 15 and comprising upper and lower sections 16 and 17. Section 16 has at its large end an outwardly directed flange 18 bolted to the flange 12. The small end of section 16 is received and welded in an opening in a plate 19 perpendicular to the cone axis and adapted to support the cyclone on horizontal members 20 and 21. Gussets 22 and 23 are applied between plate 19 and the sides of section 16.

Section 17 has a top flange 24 which is clamped against the lower end of section 16 by means of a clamping ring 25 and bolts 26 so that the inner surfaces of the sections are continuous with each other and are coaxial with the cylinder 10.

The lower end of section 17 is received and welded in a ring 27 which is parallel to plate 19 and a terminal apex section 28 is clamped against the lower edge of section 17 through a clamping ring 29 and bolts 30, the lower end of portion 28

2

being received in an aperture of a plate 31 which is supported from ring 29 by means of a cage 32. As here shown, the interior surface of portion 28 is in smooth continuation of the interior surface of portion 17.

Pivoted beneath plate 31 on a vertical pin 32 is a table 33. The pin has a nut 34 threaded on its upper end for the support thereof and at its lower end has a flanged head 35 between which and the

10 bottom of the table 33 is a compression spring 36 which holds the table against the bottom of plate 31. The downwardly projecting parts are in a tubular guard 37 fixed to the bottom of the table. The table is provided with a plurality of vertical openings 38 whose upper margins are rabbeted, and set in the openings are nozzles as at 39 and 40 having upper out-turned flanges engaging the rabbets for the support of the nozzles, the nozzles being insertable and removable through an opening 31' in plate 31. Nozzles 39 and 40 have vertical bores 41 and 42 of different diameter, the bores being surmounted by counter sinks 43 and 44 whose top diameter is the same as the diameter of the opening at the lower end of portion 28.

15 By turning the table 33, the nozzles can be selectively positioned in alignment with portion 28 and in this manner the size of the apex opening is quickly changeable. Reference numeral 45 designates a hopper for the reception of the apex discharge.

Reference numeral 46 designates a cylindrical overflow hood having an outwardly flanged lower edge 47 bolted to the flange 11. The cylinder 46, as here shown, has the same diameter as the cylinder 10 and, in any event, the side wall of the hood should preferably lie within the axial projection of the cylinder 10 for the sake of compactness. Fixed in the bottom of the cylinder 46, as by welding, is a plate 48 which constitutes the top

20 of the vortex chamber. Plate 48 has a central aperture in which is fixed a vertical tubular vortex finder 49 which extends above and below, or outwardly and inwardly of, the wall. The finder has a lower cylindrical bore 50 whose diameter is substantially the same as the diameter of the spout 13 where it first intersects the cylinder 10, i. e. at the point 13', and these diameters are substantially between $\frac{1}{8}$ and $\frac{1}{4}$ of the internal diameter of the cylinder 10. The finder has a

25 lower external conical surface 51 which flares upwardly to the indicated weld fillet, thus eliminating the usual right angle wherein particles tend to collect. As here shown, the cylindrical bore 50 extends upwardly to the top of wall 48 and thereabove is conically outwardly flared.

Formed in the wall 48 is an outlet opening 53 whose lower edge is as close as possible to the top of plate 48. Reference numeral 54 designates a conduit projecting outwardly and downwardly from the opening. The top of the cylinder is closed by a wall 55 which has a central inspection opening which is surrounded by a tube 56 fixed to and projecting downwardly from the wall coaxially with the finder and with the apex opening. The wall opening is closable by means of a plug 57. Reference numerals 58 and 59 designate handles secured to wall 55 and by means of which cyclone may be lifted.

In a concentrating cyclone as shown, I have found that the best results are secured when the apex angle is between 15° and 25°. The greatest wear in use occurs in the conical portion of the cyclone and it will be evident that any of the portions 16, 17 and 28 may be readily removed for replacement. I have further found that a superior effect is obtained when the diameter of the inlet opening is substantially the same as the diameter of the top outlet, i. e., the bore 50, and when these diameters are substantially from $\frac{1}{8}$ to $\frac{1}{5}$ of the diameter of the cylindrical portion. The flow through the finder is improved when its upper portion is outwardly flared as shown at 52, and there is a better circulation around the downwardly projecting portion of the finder when its outer surface is flared upwardly as shown at 51. The illustrated overflow hood is of advantageously small size. The effluent rising through the finder builds up and rotates against the side wall of the hood and is effectively disposed of through the side wall opening. As shown in Figure 3, this opening may be tangential in the direction of rotation of the effluent in the hood.

Typical dimensions are as follows: height from top of hood to bottom of section 17, 1060 mm.; height of hood chamber, 175 mm.; height of cylindrical receiving chamber, 100 mm.; height of section 16, 347 mm.; height of section 17, 390 mm.; diameter of cylindrical portions, 350 mm.; diameter of opening at lower end of section 17, 80 mm. The diameter of the top outlet (bore 50) will be from about 35 mm. to about 70 mm.

In Figure 4, the tapered portion 15' of the cyclone is shown as including separable sections 16' and 17' whose inner surfaces are convexed inwardly or toward each other, the curvature decreasing downwardly but preferably giving a mean angle of from about 15° to 25°. It will be evident that these curved sections can be substituted for the straight sections 16 and 17 of Figure 1.

In Figure 2, the lower portion 60 of the section 17'' is made cylindrical and is provided at its lower end with an outward flange 61 having a bottom internal rabbett. Reference numeral 62 designates a conical portion having the same angle as portion 17'' received in the cylindrical portion and terminating at the upper end thereof, the outer upper margin of portion 62 being beveled so that a flush joint is provided. Portion 62 has a bottom flange 63 received in the rabbet of flange 61 and held by means of a flanged tubular fitting 64 bolted to the flange 61. Also clamped between the flange 63 and the fitting 64 is a nozzle 65 whose inner surface, as here shown, is in smooth continuation of the inner surface of portion 62. However, the form of nozzle 65 may be varied to provide apex openings of varied diameter. Reference numeral 66 designates a guard threaded on fitting 64 and pro-

vided with an aperture through which the nozzle discharges.

It will be understood that the invention is susceptible of variations beyond those described and is not restricted in matters of the form and relation of parts except as in the following claims.

I claim:

1. In a cyclone, a vortex chamber including a relatively short cylindrical chamber portion and a relatively long tapered chambered portion, said portions being coaxial, the mean angle of taper of said tapered chamber portion being between 15° and 25°, said tapered chamber portion being circular in transverse section and including a circular and central apex outlet, a tangential feed pipe debouching into said cylindrical chamber portion, the inlet mouth of the feed pipe being flush with the inner surface of said cylindrical chamber portion, an end wall for said cylindrical chamber portion having a central outlet opening, a tubular member fitted in the outlet opening and extending from both sides of said end wall, but having its portion which extends into said cylindrical chamber portion terminate adjacent the plane at which said tapered chamber portion joins said cylindrical chamber portion, the portion of said tubular member which lies within said cylindrical chamber portion having a bore of uniform diameter and of substantially the same cross-sectional area as the inlet mouth of said tangential feed pipe, and the exterior surface of said portion flaring outwardly from its terminal end to said end wall of said cylindrical chamber portion, the portion of said tubular member which lies beyond said end wall having a bore which flares outwardly away from said end wall.

2. In a cyclone, a vortex chamber including a relatively short cylindrical chamber portion and a relative long tapered chamber portion, said portions being coaxial, the mean angle of taper of said tapered chamber portion being between 15° and 25°, said tapered chamber portion being circular in transverse section and including a circular and central apex outlet, a tangential feed pipe debouching into said cylindrical chamber portion, the inlet mouth of the feed pipe being flush with the inner surface of said cylindrical chamber portion, an end wall for said cylindrical chamber portion having a central outlet opening, a tubular member fitted in the outlet opening and extending from both sides of said end wall but having its portion which extends into said cylindrical chamber portion terminate short of said tapered chamber portion, the portion of said tubular member which lies within said cylindrical chamber portion having a bore of uniform diameter and of substantially the same cross-sectional area as the inlet mouth of said tangential feed pipe, and the exterior surface of said portion flaring outwardly from its free end to said end wall, the portion of said tubular member which lies beyond said end wall having a bore which flares outwardly away from said end wall.

3. In a cyclone, a vortex chamber including a relatively short cylindrical chamber portion and a relative long tapered chamber portion, said portions being coaxial, the mean angle of taper of said tapered chamber portion being between 15° and 25°, said tapered chamber portion being circular in transverse section and including a circular and central apex outlet, a tangential feed pipe debouching into said cylindrical chamber portion, the inlet mouth of the feed pipe being flush with the inner surface of said cylindrical chamber portion, an end wall for said cylindrical chamber portion having a central outlet opening, a tubular member fitted in the outlet opening and extending from both sides of said end wall but having its portion which extends into said cylindrical chamber portion terminate short of said tapered chamber portion, the portion of said tubular member which lies within said cylindrical chamber portion having a bore of uniform diameter and of substantially the same cross-sectional area as the inlet mouth of said tangential feed pipe, and the exterior surface of said portion flaring outwardly from its free end to said end wall, the portion of said tubular member which lies beyond said end wall having a bore which flares outwardly away from said end wall, an overflow hood beyond said end wall, said hood being cylindrical in transverse section and its peripheral wall being in continuation of the peripheral wall of the said cylindrical portion, and an outlet pipe extending tangentially from said hood and in a direction to directly receive material rotating in said hood.
